INVENTOR:

UNITED STATES PATENT OFFICE

ARTHUR B. MUELLER, OF KANSAS CITY, MISSOURI

REDUCING APPARATUS

Application filed May 19, 1930. Serial No. 453,771.

My invention relates to reducing apparatus and my object is to provide means whereby superfluous flesh may be removed from the person by physical exercises carried out with the use of the apparatus.

A further object is to provide an apparatus of this character which is well adapted for the purpose intended, is compact in form and may be supported from a door casing or other suitable object.

In order that the invention may be fully understood, reference will now be had to the accompanying drawings, in which:

Fig. 1 is a broken side elevation of the apparatus.

Fig. 2 is a broken front elevation of the apparatus.

Fig. 3 is a horizontal sectional view on line 3—3 of Fig. 1.

Fig. 4 is a broken vertical section on line 4—4 of Fig. 3.

Fig. 5 is a section on line 5—5 of Fig. 2.

Fig. 6 is a section on line 6—6 of Fig. 1.

Fig. 7 is a detail of one of a pair of links employed in carrying out the invention.

Referring in detail to the different parts, 2 designates a standard which consists preferably of a suitable length of pipe secured at its ends in upper and lower housings 4 and 6, respectively, which are similar to each other in shape and enclose suitable means whereby they may be firmly secured to a door casing A or other suitable support.

As shown by Fig. 5, each housing is secured to the casing A by means of a hook 8, a link 10 and a screw 12. The hook 8 has threads 14 so that it may be screwed into the casing A, while the screw 12 is threaded into one end of the link 10, which latter engages over the outer end of the hook 8. The outer end of the screw 12 is provided with suitable means whereby it may be readily rotated to tighten up the link 10 and force the housing 4 firmly against the casing A, said means in the present instance being shown in the form of a thumb piece 16 bearing against the front end of the housing 4.

18 designates a bearing having a rearward extension 20 which may be firmly secured at any elevation upon the standard 2 by suit-

able means such as a clamping member 22 which is firmly drawn against said standard by screws 24 and 26 provided with handles 28 and 30, respectively, whereby they may be readily rotated.

The bearing 18 supports a rockable shaft 32 which is preferably of tubular formation as shown so that it may be filled with grease or other lubricant which is free to flow out through diametrically opposed ports 34 and lubricate the bearing 18 and a cap 36, which latter holds the shaft 32 in said bearing 18.

The bearing cap 36 is yieldably held in position upon the shaft 32 by suitable means such as bolts 38 which pass upwardly through registering holes in the bearing 18, the cap 36 and a yoke 40, which latter is pressed downwardly upon a coil spring 42 and in turn causes the latter to press downwardly upon the bearing cap 36. The desired pressure upon the yoke 40 is obtained by suitable means such as nuts 44 threaded upon the upper ends of the bolts 38, which latter are provided at their lower ends with thumb pieces 46 whereby they may be readily rotated in either direction. The nuts 44 are held from rotating with the bolts 38 by means of flanges 48 projecting upwardly from the yoke 40.

The upper portions of the bolts 38, the yoke 40 and the spring 42 are enclosed within a casing 50 provided with a cap 52 having a removable cover plate 54, so that access may be had to a nut 56 threaded upon the upper end of a bolt 58 with which it cooperates in holding the casing 50 and the cap 52 in assembly with the bearing cap 36. The bolt 58 extends through a hole in the yoke 40 and is secured to the bearing cap 36 as shown by Figs. 4 and 6.

By enclosing a large number of the parts within the housings 4, 6 and 50, all danger of the operator of the machine being scratched or otherwise injured by the various parts is eliminated.

The hollow shaft 32 is closed at one end with a knob 60 and at its opposite end with a hand lever 62 which is oscillated by the party taking treatment for the removal of superfluous flesh. In practice resistance to the

operation of the hand lever 62 may be regulated as desired by adjusting the bolts 38 in a manner to cause the spring 42 to exert increasing pressure upon the bearing cap 36 until the desired frictional resistance is had on the shaft 32.

From the foregoing description taken in connection with the drawings, it is apparent that I have provided a reducing apparatus embodying the advantages above pointed out, and while I have shown and described one form of the invention I reserve all rights to such other forms and modifications thereof as properly fall within the spirit and scope 15 of the invention as claimed.

Having thus described my invention, what I claim and desire to secure by Letters Patent, is:

1. In an apparatus of the character described, a tubular shaft adapted to hold a lubricant and provided with outlet ports, a hand lever for operating said shaft and closing one end thereof, suitable means closing the opposite end of said shaft, and supporting means frictionally engaging said shaft for retarding the operation thereof.

2. An apparatus of the character described consisting of a suitably supported bearing, a shaft operably mounted in said bearing, 20 a cap engaging said shaft, a spring resting against said cap, a yoke, screw means for drawing said yoke against said spring to cause the cap to frictionally engage the shaft, a housing resting on said cap and enclosing 25 the spring and the yoke, and manually controlled means for actuating said shaft.

3. An apparatus of the character described consisting of a suitably supported bearing, 30 a tubular grease holding shaft operably mounted in said bearing and provided with outlet ports, a cap engaging said shaft, a spring resting against said cap, a yoke, means for drawing said yoke against said spring to cause the cap to frictionally engage the shaft, 35 means including a hand lever for closing the ends of the shaft, a housing resting on the cap and enclosing the spring and the yoke, and screw means for holding said housing on the cap.

4. An apparatus of the character described 40 consisting of a standard, exercising means mounted upon said standard, housings connected to the ends of said standard, hooks adapted to be secured to a support, links engaging said hooks, and screws threaded in 45 said links to draw the latter taut and force the housings firmly against the support.

5. An apparatus of the character described 50 comprising a suitably supported standard, a support vertically adjustable upon said standard, means cooperating with said support for securing the latter at any point of its adjustment upon the standard, and frictional exercising means carried by said support.

6. An apparatus of the character described comprising a suitably supported standard, a support vertically adjustable upon said standard, a clamping member vertically adjustable upon said support, manually controlled screw means for securing the support and said clamping member at any point of their adjustment upon the standard, and exercising mechanism carried by said support.

In testimony whereof I affix my signature. 75
ARTHUR B. MUELLER.
